UNITED STATES PATENT OFFICE.

LEON L. CILLEY AND SAMUEL J. BRION, OF ADDISON, NEW YORK.

HASP-HOOK.

1,102,720.

Specification of Letters Patent. Patented July 7, 1914.

Application filed April 9, 1913. Serial No. 780,027.

To all whom it may concern:

Be it known that we, LEON L. CILLEY and SAMUEL J. BRION, citizens of the United States, residing at Addison, in the county of Steuben, State of New York, have invented certain new and useful Improvements in Hasp-Hooks; and we do hereby declare the following to be a full, clear, and exact description of the invention, such as will enable others skilled in the art to which it appertains to make and use the same.

This invention is directed to improvements in hooks especially adapted for use in connection with screen doors.

15 The invention has for its object to construct a hook of this character in such a manner that the same, when engaging the fastening eye will be prevented from becoming accidentally unhooked.

20 A further object of the invention is to form a hook of this character from a single length of metal being so formed that the free end thereof when engaged in the keeper will be firmly hooked, but may be readily 25 disengaged when desired.

With these and other objects in view, this invention resides in the novel features of construction, formation, combination and arrangement of parts to be hereinafter more 30 fully described, claimed and illustrated in the accompanying drawing, in which:—

Figure 1 is a front elevation of the hook showing the same in the position previous to its engagement with the keeper. Fig. 2 is a 35 similar view, the keeper being shown in section and the hook engaged therewith.

Referring to the drawing, the numeral 1 designates a portion of the door jamb and 2 the side rail of a screen door or the like.

40 The hook comprises a shank 3 having one of its ends formed with an eye 4 which interlocks with the screw eye 5, said screw eye being fastened to the door jamb 1 so that the hook may freely swing. The other end 45 of the shank 3 terminates in a hook 6 which is split so as to provide resilient furcations 7.

The furcations 7 are formed intermediate their lower ends with shoulders 8 which terminate in inclined arms 9. The inclined 50 arms 9 terminate in convergingly arranged fingers 10, and owing to the fact that the furcations 7 are resilient said fingers will be

held spaced apart previous to, and after engagement with the fastening eye or keeper 11 which is attached to the side rail 2 of the 55 door.

When it is desired to latch the door, and when the hook is in the position as shown in Fig. 1 it is only necessary to swing the same so that the fingers 10 engage the keeper 60 11, whereupon exerting slight pressure upon the hook the inclined arms 9 will engage the keeper and force the fingers toward each other, after which the hook assumes the position as shown in Fig. 2, and at which 65 time the fingers have expanded so that shoulders 8 engage the under side of the keeper, thus preventing the accidental disengagement of the hook from the keeper. To unlatch the hook it is only necessary to grasp 70 the fingers 10 and force them toward each other, thereby disengaging the shoulders 8 from the keeper and permitting the hook to be readily disengaged so that the door can 75 be opened.

It is obvious that the device can be used upon windows, blinds, or doors other than screen doors, and further that when the device is in use the door or window to which it is attached cannot be opened from the out- 80 side.

What is claimed is:—

A device of the class described comprising a body having formed at one end an eye for interlocking with an eye, the other end of said 85 body portion terminating in a hook formed with resilient furcations, shoulders formed upon the lower ends of the furcations and terminating in inclined arms which in turn terminate in normally spaced fingers, a 90 keeper through which the normally spaced fingers pass, said keeper when engaging the inclined arms force the fingers together to permit the shoulders to move toward each other to pass through the keeper for engagement therewith.

In testimony whereof, we affix our signatures, in the presence of two witnesses.

LEON L. CILLEY.
SAMUEL J. BRION.
